SAFETY AND ADJUSTING DEVICE FOR CORD REEL

Rodger F. Becker, Kalamazoo, Mich.

Application June 17, 1955, Serial No. 516,268

14 Claims. (Cl. 242—107)

This invention relates to a safety device for counterbalanced reel assembly and more particularly relates to a safety device for preventing rotation of a spring-balanced reel if the spring should break.

Cord reels of the general type here involved are used in a variety of places and for many purposes. While the problem of safetying the reel in the event of spring breakage is present in most, or all, of these applications, one specific example is sufficient to illustrate its nature. It is known to provide a spring counterbalanced tool supporting reel above a work station. A cord, which supports a tool, is normally wound about the reel and suspends the tool in an out-of-the-way position when not in use. The workman may pull on the cord to unwind it from the reel and thereby place the tool in operative position. When the workman is through using the tool, he will release it and the spring will cause the reel to rotate to wind up the cord. It sometimes happens that the counterbalancing spring breaks and, unless movement of the reel is prevented, the cord unwinds and the tool drops down. Injury to the workman, the tool and other equipment may occur. This problem has been recognized and numerous attempts have been made to provide a satisfactory safety device to prevent unwinding of the reel if the counterbalancing spring should break. In addition, it is frequently desirable to provide means for adjusting the amount of force exerted by the counterbalancing spring on the reel so that the reel can support tools of varying weights. Heretofore, it has not been possible to provide a combination of a simple and effective safety device which will prevent the spring from unwinding and also provide a tension adjusting means for the counterbalancing spring within the same unit in which certain elements perform a dual function and aid in the operation of the safety device and the spring adjusting means.

Accordingly, it is an object of this invention to provide an improved safety lock for a counterbalancing reel.

It is a further object of this invention to provide a safety lock for a counterbalancing reel which safety lock is also provided with means to adjust the tension of the counterbalancing spring.

It is a further object of this invention to provide an improved and simplified safety lock and tension adjusting device.

It is a further object of this invention to provide a tension adjusting device and a safety lock in which certain elements function both as part of the tension adjusting device and as part of the safety lock.

Other objects and advantages will be apparent to those with knowledge of this type of equipment upon reading the following specification and inspecting the accompanying drawings in which:

Figure 1 is a front view of a tool balancing reel embodying my invention, partially broken away.

Figure 2 is a sectional view taken along the line II—II of Figure 1.

2

Figure 3 is a sectional view taken along the line III—III of Figure 1.

In meeting the objects and purposes set forth as well as others related thereto, there is provided, in general, 5 a spring pressed rod provided with a locking pin. The rod is urged toward a locking position wherein it can engage lugs formed on the reel to prevent the reel from rotating but is prevented from actually moving so long as the counterbalancing spring is unbroken. The rod 10 is mounted for longitudinal movement and is provided with a worm which is adapted to adjust the tension of the counterbalancing spring when the rod is moved longitudinally.

Referring to the drawings in detail, there is shown in 15 Figure 1, a housing 10 for the cord reel. The housing is provided with a yoke member 11 pivotally mounted thereon which is adapted to be engaged by any suitable supporting means, such as a hook, to support the housing in an elevated position above the work station. The housing 10 is provided at its lower end with a cord guiding device 12.

The housing 10 is divided into two longitudinally split sections 13 and 14. Section 13 is provided with a raised internal boss 15, which is adapted to rotatably support 20 one end of a shaft 16. Section 14 is likewise provided with a raised internal boss 17 which journals the other end of shaft 16. A cord reel 18 is supported on shaft 16.

The cord reel includes a pair of end plates 19 and 20. 30 The end plates are formed with raised bosses 21 and 22, respectively. Bearing means 23 and 24 are mounted in said raised bosses and support said reel for rotation relative to shaft 16. A cylindrical, externally grooved member 25 is secured between the end plates 19 and 20. The cord 26 enters into the grooves in member 25 when the cord is wound around the reel.

End plate 20 is provided with a series of spaced, transversely extending lugs 27 which cooperate with the safety locking pin in a manner to be described in detail hereinbelow.

40 A coil spring 28 is disposed within the chamber 29 defined by the end plates 19 and 20 and member 25. The inner end 30 of the spring is fixedly connected to the shaft 16 by fastening means 31. The outer end 32 of the spring is affixed to a rod 33 by fastening means 34. 45 The rod 33 is mounted in openings in the end plates 19 and 20 and is located thereby in a fixed position on the reel 18. It is apparent that rotation of the shaft 16 relative to the reel 18 will cause a change in the force exerted by the spring 28 on the reel.

The structure described thus far is substantially conventional and may be varied widely. The parts constituting an embodiment of the invention will now be described.

55 A worm wheel 35 is keyed to the shaft 16. The worm wheel is located within a raised portion 36 of the section 14. A rod 37 is slidably disposed within the raised portion 36 adjacent the worm wheel 35. The rod has mounted thereon a worm gear 38 which meshes with the worm wheel 35. A sleeve 39 surrounds a portion of the rod below the worm gear and moves therewith. A locking pin 40 is threadedly mounted in the sleeve and projects inwardly of section 14 to a position where it is capable of contacting the lug 27 if the spring 28 should break.

60 A spring 41 normally urges the rod 37 and thereby the locking pin 40 in a direction, here radially outwardly, in which the pin 40 will contact the lug 27. As explained in greater detail hereinbelow, a force transmitted by the meshing of the worm wheel 35 and worm gear 38 normally overcomes the urging of the spring and prevents such engagement between the pin 40 and lug

27. An externally threaded plug 42 surrounds the rod 37 and is disposed in an internally threaded opening 43 in the housing section 14. The rod 37 is slidably mounted in the plug 42. The plug limits the extent of movement of the sleeve 39 and thereby the rod 37. The rod 37 is provided with an enlarged head 44 which projects outwardly from the raised portion 36. The head is shaped so that it may be engaged and rotated by a suitable tool, such as a wrench. A set screw may be inserted in the opening 45 to fix the position of the plug 42 and prevent accidental movement thereof.

Operation

With the device assembled as described above, it is apparent that the spring 28 will counterbalance the weight of the tool supported on the cord 26 and prevent it from moving downwardly unless pull is exerted on the cord. Since one end of the spring is connected to the shaft 16 it will exert a torque thereon which in turn causes a torque to be exerted on the worm wheel 35. In the disclosed embodiment the spring will be so arranged that a counterclockwise torque will be exerted on worm wheel 35 as appearing in Figure 1. The torque will be transmitted to the worm gear 38 and thereby an upward force will be exerted on the rod 37. This force must be of sufficient magnitude to overcome the urging of spring 41. So long as the spring is unbroken the rod 37 will be held in its raised position as appearing in Figure 3 and the pin 40 will not engage the lugs, 27. In this condition of the parts the reel 18 is free to rotate. If the spring 28 should break, the upward force previously exerted on the rod 37 will cease and spring 41 will cause the rod 37 to move to its lower position wherein pin 40 engages lugs 27 to prevent further rotation of the reel 18. Since this movement of the rod occurs virtually instantaneously on breakage of the spring, the rotation of the reel is stopped before any possible harm can occur.

If it is desired to adjust the counterbalancing force exerted by the spring so as to enable it to support a tool having a weight different from that for which the spring may have been previously set, the head 44 is engaged by a suitable tool and rotated. This causes rotation of the worm gear 38 which, in turn, causes rotation of the worm wheel 35. The shaft 16 will rotate relative to the reel and the spring 28 will thereby be wound or unwound depending on the direction of rotation of the head 44.

It is apparent that the direction of movement of the rod 37 can be changed from the vertically downward movement disclosed hereinabove to any suitable or desired direction by changing the position of the spring 41 and the location of the rod. The direction in which the torque is exerted on shaft 16 can be changed by changing the position of the inner end 30 of the spring 28 so that the safety device can operate in any desired direction.

Although particular, preferred embodiments of the invention have been disclosed hereinabove for illustrative purposes, it will be understood that variations or modifications thereof which lie within the scope of said invention are fully contemplated herein unless specifically stated to the contrary in the appended claims.

I claim:

1. In a cord winding device, the combination comprising: a housing; a winding reel in said housing, said reel having spaced, circumferentially arranged reel rotation preventing means formed thereon; a shaft supporting said reel, said reel being capable of rotation relative to said shaft; spring means acting on said reel and urging said reel to rotate in a direction which will cause winding of the cord thereabout, one end of said spring means being fixedly mounted on said shaft, the other

end of said spring being mounted for rotation relative to said shaft with said reel; a first gear means mounted on said shaft; a rotatably mounted rod; means urging said rod to move in one direction; a second gear means mounted on said rod and meshing with said first gear means; detent means projecting from said rod and adapted to engage said reel rotation preventing means when said spring is broken to prevent said reel from rotating; and means mounted on said rod capable of being rotated whereby rotation of said rod causes rotation of said second gear means which in turn causes rotation of said first gear means and said shaft to change the force exerted by said spring on said reel.

2. A cord winding device including the combination: 15 a main housing; a winding reel in said main housing; a series of spaced, circumferentially arranged lugs formed on said reel and extending outwardly therefrom in a direction transverse to the longitudinal axis of said reel; a shaft supporting said reel, said reel being capable of rotation relative to said shaft; a spirally wound spring acting on said reel and urging said reel to rotate in a direction which will cause winding of the cord thereabout, one end of said spring being fixedly mounted on said shaft and exerting a torque thereon and the other end 20 of said spring being fixedly mounted on said reel; a worm wheel mounted adjacent one end of said shaft; a raised portion on said main housing; a rotatable rod mounted in said raised portion, said rod being spring urged in a direction generally perpendicular to the axis of said shaft and opposed to the torque exerted on said shaft; a worm 25 mounted on said rod and engaging said worm wheel; a pin mounted on said rod projecting radially therefrom and extending into said main housing and adapted to engage said lugs.

3. A device as in claim 2 wherein one end of said rod extends outwardly of said housing, means on said one end of said rod engageable with a rotating means whereby rotation on said rod causes rotation of said worm gear and thereby causes rotation of said worm wheel and shaft to change the amount of force exerted by said spring on said reel.

4. In a cord winding device, the combination comprising: a housing; a winding reel in said housing, said reel having spaced, circumferentially arranged, reel rotation preventing means formed thereon, said reel being mounted for rotation with respect to said housing; a shaft means projecting within said reel, coaxial with the axis of rotation of said reel and rotatable with respect to said reel; a spring acting on said reel and urging said reel to rotate in a direction which will cause winding of the cord thereabout, one end of said spring being fixedly secured to said shaft means, the other end of said spring being secured to said reel; a first gear means mounted on said shaft means; a rotatably mounted rod connected with stop means movable into engagement with said reel rotation preventing means; means urging said rod to move said stop means into engagement with said reel rotation preventing means; a second gear means mounted on said rod and meshing with said first gear means, said spring acting through said first and second gear means, to urge said rod to move said stop means out of engagement with said reel rotation preventing means so long as said spring is unbroken; and means mounted on said rod capable of being rotated, whereby rotation of said rod causes rotation of said second gear means, which in turn causes rotation of said first gear means and said shaft means with respect to said reel to change the force exerted by said spring on said reel.
